(57) **CLAIM**

The ornamental design for a grill, as shown and described.

DESCRIPTION

FIG. 1 is a perspective view of my new design for a grill;

FIG. 2 is a front elevational view thereof;

FIG. 3 is a right elevational side view, the left elevational view being a mirror image thereof;

FIG. 4 is a back elevational view thereof;

FIG. 5 is a top plan view thereof;

FIG. 6 is a perspective view in second orientation thereof.

FIG. 7 is a perspective view of a second embodiment of my new design for a grill;

FIG. 8 is a front elevational view thereof;

FIG. 9 is a right elevational side view, the left elevational view being a mirror image thereof;

FIG. 10 is a back elevational view thereof;

FIG. 11 is a top plan view thereof; and,

FIG. 12 is a perspective view in second orientation thereof.

The phantom lines in FIGS. 1 and 7 depict an environment of our new design and form no part of the claimed design.
